UNITED STATES PATENT OFFICE.

GERTRUDE KENNEDY LANG, OF WAYMART, PENNSYLVANIA.

TELESCOPE DARNER.

Application filed December 21, 1925, Serial No. 76,835.

This invention relates to a device for darning purposes, such as the darning or mending of stockings, socks and the like.

The object of the invention is the construction of a simple and efficient darning device which is easily inserted in the stocking or sock and then the clamping spring is quickly positioned upon the body of the device, and the broad handle is quite restful to the hand of the user.

With the foregoing and other objects in view, my invention comprises certain novel combinations, constructions and arrangements of parts as will be hereinafter fully described, illustrated in the accompanying drawings and more particularly pointed out in the appended claims.

In the drawings:

Figure 1 is a view in side elevation of a darning device constructed in accordance with the present invention, while

Figure 2 is a top plan view of the same.

Figure 3 is a central vertical sectional view of the device illustrated in Figure 1.

Figure 4 is a central, vertical sectional view of another embodiment of my darning device.

Figure 5 is a perspective view of the handle, before being placed upon the body, of the device shown in Figure 4.

Figure 6 is a fragmentary view, in elevation, of the body of the device shown in Figure 4.

Referring to the drawings by numerals, 1 designates a tall or elongated cylindrical body which is provided at its center or middle with an inwardly extending portion producing an annular groove 2, in which groove is seated the coil spring 3 for holding the sock or stocking tightly in position upon the cylindrical body 1.

The broad handle 3 affords an efficient member to be grasped by the hand of the user and by reason of its broad structure, the user of my darning device does not soon become tired in performing the tedious work of darning an article. The inner end of the handle 3 is bent at right angles and is curved at 4 to fit snugly against the curved side face of the cylindrical body 1. Suitable fastening means such as rivets 5 may be used to fasten the transversely-curved inner end 4 to the body 1. The top face of the broad handle 3 is in the same horizontal plane with one edge or side of groove 2, whereby the handle acts as a guide to quickly direct the spring 3 into

the groove; this is an important improvement, to wit: groove 2 and the upper face of the handle registering, as it facilitates the fastening of the article on my telescope darning during the use or operation of the device.

In the embodiment shown in Figures 4 to 6, I have illustrated a simplified means for attaching the handle to the cylindrical body. In this embodiment, the handle 3^a is provided on the lower end of the curved angularly disposed portion 4^a with a depending lip 6; at the juncture of the portion 4^a and the body of the handle 3^a, I cut out a tongue 7 which tongue is threaded through the elongated aperture 8, and then the tongue is bent down against the inner face of the body 1 as clearly shown in Figure 4; the lip 6 being bent up around the lower edge of body 1; by this means of fastening, I eliminate either rivets 5 or soldering, to secure the handle to the body 1. This is a very simple structure, for the body and handle can be stamped by automatic machinery and the handle quickly placed against the body and the tongue and lip bent for securely fastening the handle thereto. In this embodiment, it will be seen that the groove 2 registers with the top of the handle, so that when the operator places the coil spring around the body 1, bringing the spring into contact with the handle and then releasing the spring, so spring will be automatically guided into the groove.

I call my darning device a telescope darning, because it is inserted quite a ways into the article, affording a good surface exposed to the darning operation with the handle easily and restfully held in the hand of the operator, and the article securely held in a position on the body by my efficient spring arrangement.

While I have described the preferred embodiments of my invention, and illustrated the same in the accompanying drawings, certain minor changes or alterations may appear to one skilled in the art to which this invention relates, during the extensive manufacture of the same, and I, therefore, reserve the right to make such changes or alterations as shall fairly fall within the scope of the appended claims.

What I claim is:

1. In a device of the class described, the combination of an elongated cylindrical body provided with a circumferential groove, a

- handle provided at its inner end with a right angled extension, said right angled extension being curved throughout its length in cross section to fit snugly against the curved outer face of said cylindrical body, the upper or outer face of said handle registering with said groove, means securing the right angled extension of the handle to said body, and a coil spring seated in said groove.
- 5 2. In a device of the class described, the combination of a body provided with a groove and with an aperture at one side of said groove, a handle provided with a tongue and a lip, said tongue fastened in said aperture and said lip fastened against one edge of said body, and clamping means in said groove.
- 10 3. In a device of the class described, the combination of a cylindrical body provided with a groove and an elongated aperture parallel with and contiguous to said groove, a handle provided with a right angled extension at its inner end, said extension curved in cross section to fit against said cylindrical body, said handle being cut at said extension to produce a tongue, said extension provided with a depending lip, said tongue threaded through said elongated aperture and bent upon the body, said lip bent around the lower edge of the body and against the inner face thereof, and a coil spring in said groove.
- 15 20 25 30
- In testimony whereof I hereunto affix my signature.

GERTRUDE KENNEDY LANG.
